CLAIM

The ornamental design for an interchangeable button assembly, as shown and described.

DESCRIPTION

FIG. 1 is an exploded, front perspective view of an interchangeable button assembly showing my new design. The cap, base and fastener elements are shown separately for clarity of illustration.

FIG. 2 is an exploded rear perspective view thereof;
FIG. 3 is a top view of the interchangeable button assembly;
FIG. 4 is a bottom view thereof;
FIG. 5 is a side view of the assembled interchangeable button assembly;

FIG. 6 is a top view of the base and fastener elements shown assembled for clarity of illustration;

FIG. 7 is a bottom view of the sub-assembly of the base and fastener shown assembled for clarity of illustration; and,
FIG. 8 is a side view of the sub-assembly of the base and fastener shown assembled for clarity of illustration.

The broken lines are included for the purpose of illustrating unclaimed portions of the finger interchangeable button assembly and form no part of the claimed design.
